UNITED STATES PATENT OFFICE.

ENOCH STEWART, OF BATTLE CREEK, MICHIGAN.

IMPROVEMENT IN CURRENT WATER-WHEELS.

Specification forming part of Letters Patent No. 36,115, dated August 5, 1862.

To all whom it may concern:

Be it known that I, ENOCH STEWART, of Battle Creek, in the county of Calhoun and State of Michigan, have invented a new and Improved Water-Wheel; and I do hereby declare that the following is a full, clear, and exact description of the same, reference being had to the accompanying drawings, making a part of this specification, in which—

Figure 1 is a side view of my invention. Fig. 2 is an end view of the same.

Similar letters of reference indicate corresponding parts in the two figures.

This invention relates to an improved water-wheel of that class which are driven by the force of a stream and are commonly termed "current-wheels."

The object of the invention is to obtain a simple and durable wheel of the class specified, and one which will operate without having its buckets subjected to much wear and tear, as is the case with all of these wheels in which the current or force of the stream is made to adjust or operate the buckets.

My invention consists in placing a wheel upon a horizontal shaft and providing it with buckets, which are attached by joints or hinges in such a manner that the buckets will by their own gravity adjust themselves in proper working position previous to entering the water, and then by the same means fall so as to assume a closed position as they leave the water.

To enable those skilled in the art to fully understand and construct my invention, I will proceed to describe it.

A represents a horizontal shaft on which a wheel, B, is placed. This wheel may be constructed of two rims, *a a*, connected to the shaft A by radial arms *b*, the latter being connected by cross-bars *c*. The rims *a a*, arms *b*, and cross-bars *c* may be of wood. The shaft A may be of wood or metal. The rims *a a* are made of a depth equal to the depth of the buckets *d*, which are of square form and are attached radially to the outer and inner sides of the rims *a a* by hinges or joints *e*, which admit of the buckets swinging freely on the rims. These hinges or joints may be formed by attaching metal straps or loops *f* to the rims *a a* and having the former fitted in recesses *g* at the inner parts of the buckets, as shown in both figures.

In the rims *a a* there are fitted pins *h*, the latter passing entirely through the former and projecting from the rims at both sides. These pins are fitted centrally in the rims and at such

points as to prevent the buckets *d* from swinging outward from the rims beyond a right-angular position therewith, as will be fully understood by referring to Fig. 1, in which three buckets are shown in contact with their pins.

Any proper number of buckets *d* may be employed, according to the diameter of the wheel, and they may be of wood or metal.

The operation is as follows: The wheel is so adjusted that the rims *a a* will be submerged in the stream, the shaft A being supported by any suitable framing, and the pins *h* being at the back sides of the buckets, so as to form stops for the same to prevent the water or current forcing them beyond a right-angular position with the rims *a a*. The direction of the current is indicated by the arrow in Fig. 1, and the surface of the stream is indicated by the red line in the same figure. The current in thus acting upon the buckets rotates the wheel, and as each bucket leaves the water it closes by virtue of its own gravity, and remains closed until it passes over the shaft A and commences to descend, when, from the same cause, it opens and is ready to receive the action of the current as it enters the water.

By this arrangement it is believed that a very great advantage is obtained over the current-wheels hitherto devised, for the buckets, not being dependent on the action of the current to open them, are not subjected to the wear and tear to which they would otherwise be. The current in opening the buckets causes a violent slamming of the same, and they are liable to be wrenched from their hinges or broken by the concussions.

My invention may be constructed at a small cost, and readily repaired when repairs are necessary.

I do not claim, broadly, a current or water wheel provided with buckets connected to it by hinges or joints; but

I do claim as new and desire to secure by Letters Patent—

A current-wheel, B, placed on a horizontal shaft, A, and provided with buckets *d*, attached to its rims *a a* in a radial position by means of hinges or joints *e*, and used in connection with the pins or stops *h*, all arranged to operate substantially as set forth.

ENOCH STEWART.
